UNITED STATES PATENT OFFICE

KENNETH JAMES RENNIE ROBERTSON, OF LONDON, ENGLAND, ASSIGNOR TO CARRIER
ENGINEERING COMPANY LIMITED, OF LONDON, ENGLANDMETHOD AND APPARATUS FOR CLEANING ARTICLES, PARTICULARLY METALLIC
GOODS

REISSUED

Application filed August 25, 1928, Serial No. 302,038, and in Great Britain June 13, 1928.

The main object of the present invention is to provide a method and apparatus for cleaning articles, more especially metal articles and castings, wherein the whole surface 5 of the articles will be subjected to solvent action, preferably combined with a scrubbing or washing movement, and a second object is to provide a cleaning plant from which the articles emerge in a dry condition.

10 A further object is to provide for the continuous use of a comparatively small body of solvent by re-circulating the solvent through the cleaning plant and extracting any dissolved grease and dirt after its contact with the dirty articles, whereby a supply 15 of clean vapour to the plant is obtained.

A still further object is to prevent losses of the highly volatile solvents employed by leakage to atmosphere and thereby render operation of plant according to the invention 20 economical.

In accordance with the present invention a method of cleaning greasy articles consists in immersing them in vapour solvent for the 25 grease while at a temperature below the condensation temperature of such vapour solvent, whereby the vapour condenses on the articles dissolving the grease which falls off in solution and thus warms the articles, leaving them dry.

To obtain continuous cleaning the articles are preferably traversed through a bath of the vapour solvent, the grease charged condensate of which is regenerated and resupplied to the bath as clean vapour after extraction of the grease, and the bath is thus maintained charged with the clean vapour solvent necessary for effective cleaning of the articles.

The solvents used are preferably those 30 whose vapours are heavier than air and such as will readily remove grease, wax or oils from metallic goods without any chemical effect on those goods, and the employment of such vapours permits of an open trough or chamber being used, the vapour lying near the bottom of the trough or chamber, and to a predetermined height controlled by the admission of vapour, and if desired also by refrigerating means located in the upper 35 zones of the trough or chamber which cause

any vapour rising to their vicinity to condense and fall to the base of the chamber.

Preferred apparatus for cleaning greasy articles according to the invention, includes a bath of vapour solvent, a conveyor traversing articles through such bath, and regenerating stills extracting the grease charged condensate from the bath, regenerating and maintaining the bath charged with clean vapour through inlets connecting the bath with the stills.

Preferably the inlets are disposed so as to produce a circulating movement of the vapour in the nature of a convection current, and in addition such inlets are preferably duplicated or multiplied, each set of inlets having an associated regenerating apparatus so that one apparatus may be disconnected and cleaned by the ejection of accumulated grease and dirt, while the other supplies the bath 65 with the regenerated clean vapour.

At the bottom of the bath outlets are provided for collecting the condensation products and these outlets are connected to regenerating apparatus for reforming the vapour 75 from the condensation products, the regenerators being preferably directly connected to the vapour inlets to the trough to form a closed cycle and so that a continuous supply of vapour is assured.

A cleaning plant according to the invention may be automatically controlled by thermostats associated, for instance, with the heaters of the regenerating apparatus so that their operation is regulated according to the 85 temperature of the vapour in the bath, or according to the depth of the vapour in the bath, that is to say, that thermostats may be disposed just above the vapour bath so that when the warm vapour reaches the 90 thermostats the regeneration is cut down. Such an arrangement may be utilized in conjunction with the refrigerating zones aforesaid or alternative thereto.

The invention will be further described 95 with reference to the accompanying sheet of explanatory drawings which illustrate diagrammatically by way of example a preferred form of apparatus for carrying the invention into effect, and in which: 100

Fig. 1 is a transverse section of the apparatus showing the conveyor feed for the articles to be cleaned and the disposition of the vapour inlets with regard thereto; and 5 Fig. 2 is a section on the line II—II of Fig. 1 showing the vapour circuit and the relative arrangement of the cleaning section of the conveyor.

Referring now to the drawing 1 is a bath 10 in the form of a U shaped duct in which is disposed a conveyor 2 mounted on feed rollers 3 and preferably adapted for the continuous feeding of a succession of the articles 4 to be cleaned, which are shown suspended 15 from the conveyor 2 and which—dependent on the form of the article—may either be carried in baskets mounted on the conveyor or suspended direct therefrom by means of hooks. The articles 4 are preferably at normal or room temperature.

In the example illustrated the conveyor 2 is moving in a counter clockwise direction and the articles 4 about to be cleaned enter the bath at 5 and are discharged at 6 after 25 passage through the cleaning zone 7 of the bath 1 cleansed as required by the removal of any grease or dirt which adhered to their surfaces.

8 represents vapour inlet nozzles to the 30 cleaning zone 7, which are disposed in the vicinity of the feed conveyor 2 and the vapour—at a somewhat elevated temperature—issuing from the inlets 8 impinges on the greasy articles 4 to be cleansed, which, due 35 to their lower temperature cause condensation of the vapour on their surfaces, this condensate after dissolving the superficial grease and dirt carried by the articles 4 falling to the bottom 9 of the bath 1 from whence it 40 is withdrawn through waste pipes such as 10 and 11 and regenerated as desired.

The vapour circuit is illustrated in Fig. 2 and it will be seen that the waste pipes 10 and 11 communicate with stills 12 and 45 13 respectively in which the condensed vapour is regenerated by being boiled under the influence of sources of heat 14 and 15 disposed in association with each of the stills 12 and 13, the regenerated vapour passing 50 through conduits 16 and 17 and the nozzles 8 to the cleaning zone 7 and the collected grease and dirt being discharged from the bottom of the stills 12 and 13—say at intervals—through conduits 18 and 19 provided with suitable valves or taps adapted 55 to regulate the discharge.

As has already been mentioned the vapours utilized in the bath 1 are preferably those heavier than air, and such as will readily remove 60 grease, wax or oils from metallic goods without having any chemical effect on the goods, but even with heavier than air vapours, an excessive regeneration from the stills 12 and 13 taking place, a certain portion 65 of the vapour in the bath 1 would

leak to atmosphere unless special provision were made for its prevention. Accordingly in the upper zones of the bath 1 a series of cooling pipes 20 are disposed around the inner surface of the bath 1 through which 70 pipes refrigerant is preferably conveyed, so that on the vapour reaching the upper zones of the bath, that is in the vicinity of the cooling pipes 20, condensation is effected and the vapour falls to the base 9 of the bath and is 75 conveyed through the waste pipes 10, 11, to one or other of the regenerating stills 12 and 13.

Where desired, control of the regeneration in the stills 12, 13, may be effected by 80 means of a thermostat such as 23, which may, if desired, replace the series of cooling pipes 20, or may be used in addition thereto, such thermostat 23 being arranged so that when subjected to the influence of the warm vapour it operates to close one of the waste pipes such as 11 and a vapour supply pipe such as 17 by valves 31 and 30 and simultaneously cut off the supply of heat to the corresponding still 13 by the closing of 90 valve 25, so that the condensate is removed from the bath only through the waste pipe 10 and regeneration only continued in the still 12 until desired conditions are restored, when the thermostat 23 will reopen the waste pipe 11, the vapor supply pipe 17, and simultaneously supply heat to the still 13, thereby 95 commencing regeneration of the vapour therein.

The thermostat 23 is preferably disposed 100 somewhat above the cleaning zone 7, say in the entry 5 or the exit 6, and remote from the influence of the cooling pipes 20, providing a refrigerating zone therefor.

A particular form of still utilized is illustrated in Fig. 2 of the drawing and is provided with a convex base 24 below which is disposed a suitable source of heat for example, a gas burner 14 or 15, the supply of gas to which may be under control from the thermostat 23 by means of a diaphragm valve 25, and the still being provided with a discharge conduit such as 18 or 19 for the collected grease and dirt.

In operation and using as 18 or the cleansing medium or solvent, say dichlorethylene having a boiling point in the neighbourhood of 125° F., the stills are arranged to deliver the vapour through the inlets 8 at a temperature of say 120° F. and the article to be cleaned possessing a normal temperature of say 60° F. are fed to the conveyor 2 at 5 and conveyed into the cleaning zone 7, where, by reason of their relative coldness, condensation of the solvent vapour is effected on their surfaces, whereby the grease and dirt coating is dissolved off in solution which—as liquid—falls to the base 9 of the bath and passes through the waste pipes 10 and 11 to the stills 12 and 13.

12 and 13 and the articles are dried by the heat from the condensing vapour.

Regeneration is effected in the stills under control of the thermostat 23, the regenerated vapour being supplied in the cleaning zone 5 through the vapour inlets 8 and the residue grease and dirt remaining in the base of the stills 12 and 13 from whence it is collected as required.

10 Where desired, the conveyor 2 may be arranged so that the articles 4 after cleaning are passed through a chamber in which hot air is circulated, in order to remove the last traces of solvent, or alternatively a separate 15 conveyor may be used for this purpose.

An alternative method of regenerating the vapour and simultaneously separating the collected grease and dirt is illustrated in the dotted lines in Fig. 1 where—in the base 9 20 of the bath 1—are shown a series of heating pipes 26 through which may be passed steam or other media adapted to maintain the pipes at a temperature sufficient to effect vaporization of any condensed liquid falling 25 in their vicinity, such temperature depending on the particular vapour or solvent used, and being conveniently controlled by suitable thermostats.

It may be found preferable to arrange the 30 series of refrigerant cooling pipes 20, so that they are hingedly secured to permit of the opening of the bath to atmosphere at the entry 5 and the exit 6 being suitably regulated, while although the apparatus shown includes 35 two stills 12 and 13 for regenerating the vapour, more of these stills may be provided if desired, each preferably under thermostatic control, so that individual stills may be dismantled or cleaned while the apparatus 40 remains in operation.

The method of and apparatus for cleaning articles according to the invention assures complete removal of all grease from the articles, which, traversing the vapour in a direction 45 at right angles to its movement, are moved in a manner equivalent to agitating the articles in the vapour, complete, subjection of the articles to the vapour being thus ensured.

50 By ensuring that the articles entering the bath are in a relatively cold condition while the vapour is at a moderately high temperature the heat liberated by the solvent condensing on the surfaces of the articles raises 55 their temperature, thus softening any grease on their surfaces and rendering it more easily soluble whilst evaporation of any condensed solvent is ensured prior to the articles leaving the bath so that they issue in a cleaned dry 60 condition.

Further the vapour treatment according to the invention permits of the vapour penetrating to the surface of the articles to be cleaned prior to its condensation, thereby effecting an exceptionally rigorous detergent

effect with consequent complete removal of any grease and dirt from their surfaces.

Although the invention has been described with more particular reference to the treatment of metallic articles, it should be understood that it is also applicable to the cleaning of fabrics, garments, wool and other similar materials.

What I claim is:—

1. A method of degreasing surfaces, consisting in generating a vapor, collecting the vapor in a retainer open to the atmosphere, immersing a surface to be degreased within the vapor and assuring a supply of vapor sufficient to cover the surface throughout the immersion operation. 75

2. A method of degreasing objects, consisting in generating a vapor, collecting the vapor in a retainer open to the atmosphere, causing some of said vapor to condense on an object to be degreased by immersing the object within the vapor and effecting surface condensation to dissolve the grease on the object. 85

3. A method of removing oil and grease from surfaces, consisting in immersing a surface to be degreased within a vapor bath open to the atmosphere, providing a volume of vapor at a temperature greatly in excess of that of the surface, producing speedy condensation of some of the vapor on said surface and causing absorption of the grease and oil thereon, and maintaining a volume of vapor sufficient to completely cover the surface during the degreasing operation including the condensing step. 90

4. A method of degreasing materials, consisting in collecting a volume of vapor in an open container, immersing material to be degreased within the container, removing condensate from the container, and maintaining substantially a constant level of vapor within the container. 105

5. A method of degreasing, consisting in collecting vapor in a container open to the atmosphere and condensing some of the vapor on a surface to be degreased by plunging the surface within the vapor, producing a volume of condensate sufficient to dissolve and wash the grease from the surface and using the condensate to provide additional vapor. 110

6. A method of removing grease from an object to be cleaned, consisting in generating vapor from a liquid solvent, collecting the vapor in a retainer open to the atmosphere to provide a definite volume thereof, immersing an object to be degreased within the vapor to cause condensation thereof on the object, collecting the condensed vapor and regenerating that portion of the condensate adapted to be reused. 120

7. A method of degreasing surfaces and leaving them in substantially dry condition, consisting in immersing a surface within a 130

vapor bath open to the atmosphere at a temperature below the condensation temperature of the vapor in the bath, whereby the vapor will condense on the surface and raise 5 the temperature of the surface.

8. The improved method of degreasing articles which consists in continuously heating a solvent above its point of vaporization and thereby causing it to ascend in a closure 10 open to atmospheric pressure to an area cooled to a temperature below the dew point of the vaporized solvent thereby causing the same to descend and again be heated to maintain a space filled with a condensing solvent 15 through which the articles are slowly passed.

9. A degreasing apparatus comprising a vapor chamber having inlet and outlet openings toward the top thereof, a grease solvent liquid tank, means for heating said tank to 20 vaporize liquid solvent contained therein, a vapor conduit connecting said tank with said chamber, cooling coils arranged at the upper part of said chamber for condensing the vapor therein, a drain pipe connecting said 25 chamber with said tank and a conveyor arranged to carry articles through said chamber and expose them to the condensing vaporous solvent.

10. A degreasing apparatus comprising a 30 vapor chamber having ends upwardly inclined to form inlet and outlet passages, vapor condensing coils arranged in said chamber at the ceiling thereof, a pair of grease solvent liquid tanks, means for heating 35 either of said tanks, a vapor conduit connecting each of said tanks with said chamber, closure means in each of said conduits, a liquid drain from said chamber to each of said tanks, closure means in each of said 40 drains, and an endless chain conveyor arranged to pass along said chamber through the inlet and outlet opening passages.

11. A combination of apparatus for cleaning greasy articles comprising a trough having 45 an inlet and an outlet open to the atmosphere, cooling means in combination with the trough adjacent said inlet and outlet, the body of the trough being arranged at a level below said inlet and outlet, an endless 50 conveyor entering the trough from a level above said inlet and adapted to convey articles through the trough, a still for producing solvent vapors, means for feeding vapors from the still within the trough above the 55 line of travel of the conveyor and means for removing grease and dirt from the bottom of the trough, said inlet and outlet being arranged with respect to the body of the trough so that vapor heavier than air will 60 be retained in the body of the trough, wholly covering the portion of the conveyor therewithin, and have its upper level below the inlet and outlet openings.

12. Apparatus for cleaning articles comprising a trough substantially U shaped in

form, the body of the trough being the lowermost portion of the U, means for vaporizing a liquid solvent, nozzles for discharging the vapor in the upper portion of the body of the trough, means for returning 70 grease laden solvent to said vaporizing means, means for withdrawing grease and residue from the bottom of the body of the trough and returning the same to said vaporizing means and conveying means traversing the 75 body of the trough, said conveying means being adapted to carry articles to be degreased within the trough and remove them from the trough through an inlet and an outlet open to the atmosphere, cooling means 80 for preventing escape of vapor from the trough to the outer atmosphere, and means for controlling the level of the vapor within the trough.

13. A combination of apparatus for degreasing articles comprising a trough, U shaped in form, an inlet to and an outlet from said trough open to the atmosphere, cooling means for preventing escape of vapor from the trough to the outer atmosphere, the body 90 of the trough comprising the bottom portion of the U, means for evaporating a liquid solvent externally of said trough, a nozzle leading from said means to the upper portion 95 of the body of the trough, a drain from the bottom of the body of the trough leading to said means, and means for lowering articles within the trough and withdrawing them therefrom.

14. A combination of apparatus of the character described comprising a trough having an inlet and an outlet open to the atmosphere and at a level above the body of the trough means for producing solvent vapors externally of the trough, nozzles for feeding vapors from said means within and at the uppermost portion of the body of the trough, cooling means for preventing escape of vapors to the outer atmosphere and a conveyor for carrying articles to be degreased traversing the body of the trough beneath said nozzles.

15. A degreasing system having a trough at a certain level, an inlet to and an outlet from said trough open to the atmosphere at a level above the trough, means for generating solvent vapors and feeding it within the trough, means comprising condensing coils to confine the vapors within the trough and above the body thereof but below the inlet and outlet means for returning used solvent to said vapor generating means, and means for conveying articles to be degreased within the trough.

16. A combination of apparatus of the character described comprising a trough having an inlet and an outlet, means for conveying articles within the trough and removing them therefrom, means comprising a still for generating a vapor adapted to dissolve 125

grease, means for feeding the vapor within the trough, means for removing condensate and residue from the trough to said still for regeneration, said trough having cooling means for preventing escape of vapor through said inlet or outlet, and means for retaining the level of the vapor below the inlet and outlet.

17. A combination of apparatus of the character described having a trough, a vapor generator apart from said trough, an arrangement of nozzles for feeding vapor from the generator to the upper portion of the trough, means for withdrawing liquid and residue from the lower portion of the trough to the generator, one portion of the trough adapted to be completely filled with vapor from top to bottom, the trough having an extension open to the atmosphere, cooling means for confining the vapors to the trough and means for traversing articles to be degreased within the trough between the levels at which vapor is admitted and liquid and residue removed.

In testimony whereof I affix my signature.

CERTIFICATE OF CORRECTION.

Patent No. 1,905,968.

April 25, 1933.

Kenneth James Rennie Robertson.

It is hereby certified that error appears in the printed specification of the above numbered patent requiring correction as follows: In the drawing, Fig. 2, should appear as shown below instead of as shown in the patent:

Fig. 2.

Page 1, before line 1, insert the following paragraph:

This invention relates to methods and apparatus for cleaning articles, particularly metallic goods.

Page 2, line 115, strike out the number and word "18 or", and line 120, for "article" read "articles"; page 3, line 82, claim 2, for "digreasing" read "degreasing"; page 4, line 121, claim 15, after "outlet" insert a comma; and that the said Letters Patent should be read with these corrections therein that the same may conform to the record of the case in the Patent Office.

Signed and sealed this 30th day of May, A.D. 1933.

M. J. Moore.

(Seal)

Acting Commissioner of Patents.
